UNITED STATES PATENT OFFICE.

CLAES W. ROMAN, OF NEW YORK, N. Y., ASSIGNOR TO THE EAGLE PENCIL COMPANY.

DESIGN FOR A FOUNTAIN-PEN CASE.

SPECIFICATION forming part of Design No. 20,156, dated September 16, 1890.

Application filed August 18, 1890. Serial No. 382,841. Term of patent 7 years.

To all whom it may concern:

Be it known that I, CLAES W. BOMAN, of the city, county, and State of New York, have invented a new and original Design for Fountain-Pen Cases, of which the following is a specification, reference being had to the accompanying drawing, which represents in perspective a pen-case of my design.

The pen-case consists of a handle A and a cap B. As shown, the handle is formed with a milled or corrugated exterior, a rounded end, and an annular bead or projection a at the point where the cap adjoins it and the cap is formed with a plain exterior and a rounded end.

What I claim, and desire to secure by Letters Patent, is—

The design for fountain-pen cases as shown. In testimony whereof I have hereunto set my hand this 16th day of August, A. D. 1890.

CLAES W. BOMAN.
